UNITED STATES PATENT OFFICE.

EDGAR A. CONROY, OF WILKES-BARRE, PENNSYLVANIA.

MANIFOLD COVER.

Application filed July 1, 1921. Serial No. 481,868.

To all whom it may concern:

Be it known that I, EDGAR A. CONROY, a citizen of the United States, residing at Wilkes-Barre, in the county of Luzerne and 5 State of Pennsylvania, have invented certain new and useful Improvements in Manifold Covers; and I do hereby declare the following to be a full, clear, and exact description of the invention, such as will enable others skilled in the art to which it 10 appertains to make and use the same.

This invention relates to new and useful improvements in engine attachments and more particularly to an attachment adapted 15 to be applied to that type of engine used in automobiles, aeroplanes and the like, the main object of the present invention being the provision of a device adapted to be applied to the exhaust pipe and to partially 20 enclose the exhaust pipe and extend over the intake manifold whereby to conduct the heat from the exhaust pipe to the intake manifold whereby the fuel mixture passing 25 into the engine cylinders through the intake manifold will be thoroughly heated and the liquid particles vaporized before reaching the cylinders.

Another object of this invention is the provision of a device which can be quickly 30 and readily applied to an engine without the necessity of additional bolts or other fastening means, the device being retained in position by means of the bolts utilized to retain the well known form of pipe clamps 35 in position.

A further object of the present invention is the provision of a casing adapted to be arranged over a portion of the exhaust manifold and to enclose the intake manifold 40 and having formed upon its interior a plurality of longitudinally and transversely extending ribs whereby the heat from the exhaust manifold will be readily conveyed downwardly to the intake manifold to thoroughly 45 heat the fuel passing through the manifold so that when the fuel reaches the engine cylinders it will be thoroughly vaporized.

With the above and other objects in view 50 the invention consists in the novel features of construction, combination and arrangement of parts hereinafter more fully set forth, pointed out in the claim and shown in the accompanying drawings in which:

55 Figure 1 is a side elevation of an auto-

mobile engine illustrating my improved device applied thereto;

Fig. 2 is a longitudinal sectional view of my attachment, and

Fig. 3 is an interior perspective view. 60

In carrying out my invention I provide an elongated body member 1 formed of metal and provided with outstanding cup-shaped members 2 which are adapted to receive the usual pipe clamps used in securing the intake and exhaust pipes, said clamps being retained in position by means of the bolts 3 and these bolts are utilized in securing my improved device in position as each of the cup-shaped members 2 70 are provided with suitable openings 4 to receive the bolts 3, the regular securing nuts being used to clamp the device in position.

The body member 1 is provided at one end with an outstanding flange 5 which extends along one side of the body to a point adjacent the center thereof to thus form a cup-shaped enclosure at the forward end of the body. The opposite end of the body is provided with spaced flanges 6 arranged upon opposite sides of a recess 7, said recess being adapted to receive one end of the pipe clamp which is not enclosed in the body of the attachment. 75

Upon the interior of the body and formed upon opposite sides of the center or in other words, upon opposite sides of the cup-shaped members 2, are the spaced flanges 8 provided at intervals with suitable recesses 9 arranged in transverse alignment whereby to 80

receive the intake and exhaust pipes. The body portion upon the outside of the flanges 8 is provided with a plurality of transverse flanges 10 forming conducting channels whereby the heat from the exhaust pipes will be conveyed to the inlet pipes. It will be noted in the application of the device that the upper longitudinal edge rests flat against the outer surface of the exhaust manifold, the cup-shaped flange 5 embracing the end of the manifold and also forming a closure for the outer end of the device whereby to prevent the air from the fan reaching the interior of the device and carrying the heated air to the rear of the engine. 90

From the above it will be noted that I have provided a simple and durable device which can be readily cast into a single piece so as to reduce the manufacture of the de- 100

110

vice to a minimum, making the same simple in its construction so that it can be placed upon the market and sold at a very low cost.

- 5 In applying the device, the nuts are removed from the bolts 3, the device arranged in position as shown in Fig. 1, the ends of the bolts 3 projecting through the openings 4 in the members 2, the nuts then replaced 10 upon the bolts 3 and screwed down against the outer surfaces of the members 2. It will also be apparent that by having this device applied to the exhaust and intake manifolds, the intake manifold will be heated 15 so that the fuel passing therethrough will be readily heated and vaporized before reaching the engine cylinders as the heat from the exhaust manifold will be readily con-

veyed through the channel members to the intake manifold.

20

I claim:

In a device of the class described, a body member having cup-shaped recesses formed therein and provided with perforations at the bottom of the recesses, spaced flanges arranged upon opposite sides of the center of the body, said flanges being provided with transverse recesses, a plurality of transverse flanges arranged upon opposite sides of the first flanges and a cup-shaped member formed at one end of the body and projecting parallel with the flanges as and for the purpose set forth.

25

In testimony whereof I affix my signature.

EDGAR A. CONROY.
